UNITED STATES PATENT OFFICE.

ARTHUR N. McGRAY, OF NEW YORK, N. Y.

SUBMARINE MINE AND PROPELLER-ENTANGLEMENT.

1,226,348.

Specification of Letters Patent. Patented May 15, 1917.

Application filed January 30, 1915. Serial No. 5,213.

To all whom it may concern:

Be it known that I, ARTHUR N. McGRAY, a citizen of the United States, and a resident of the city of New York, borough of 5 Manhattan, in the county and State of New York, have invented a new and Improved Submarine Mine and Propeller-Entanglement, of which the following is a full, clear, and exact description.

10 This invention relates to submarine defenses against naval crafts, both of the floating and submarine types, and the general objects of the invention are to provide a defense or a system of protection for 15 coasts, harbors and the like, the defense embodying submerged elements floating a suitable depth below the surface of the water and serving as entanglements for the propellers of war crafts, whereby the latter 20 will be rendered helpless against escape and exposed to the attacks of the enemy.

In carrying out the invention the system 25 of propeller entanglements comprises a plurality of lines or cables separately laid over an area to be protected and disposed in parallel lines or intersecting lines, and each including a plurality of vertical wires spaced apart and having suitable floats whereby the 30 wires will lie close enough to the surface of the water as to be readily entangled with propellers of ships, the wires and cables being sufficiently light that they will be pulled up by propellers and more effectively entangled therewith, and if desired these 35 propeller entanglement elements and wires may include mines whereby entangled ships may be destroyed by the entangling system itself. With a system of this character the various lines can be readily laid by a craft similar 40 to a cable layer, it being merely necessary to attach at spaced points on a line, as the latter is being paid out, the buoyant propeller entangling wires or elements, and also to attach weights or anchors from time 45 to time on the line as it is paid out. It will thus be seen that an expanse of sea can be easily and quickly laid with the system of propeller entanglement.

A further object of the invention is the 50 provision in connection with the sea entanglement referred to, of a vertical net anchored at the bottom and buoyant at the top and having arranged thereon a plurality of explosive mines and dummy mines 55 suitably distributed, and as this net is lo-

cated along the border of the area protected by the entanglement a submarine which has successfully worked its way through the entanglement will be endangered by the net, and if the net is observed 60 before collision therewith the submarine will attempt to escape by moving sternward, which will expose the submarine to danger by the propeller becoming caught in the entanglements, and thereby thrown out of 65 commission.

With such objects in view, and others which will appear as the description proceeds, the invention comprises various novel features of construction and arrangement of 70 parts which will be set forth with particularity in the following description and claims appended hereto.

In the accompanying drawings, which illustrate one embodiment of the invention, 75 and wherein similar characters of reference indicate corresponding parts in all the views.

Figure 1 is a sectional view of a body of water showing a line of entanglements being laid for creating a submarine defense; 80

Fig. 2 is a plan view of a body of water showing an entanglement layer in the operation of laying entanglement lines;

Fig. 3 is a view showing a submarine 85 mine net which borders the field of entanglement;

Figs. 4 and 5 are detail views of the floating propeller entanglements; and

Fig. 6 is a detail view of one of the means 90 for attaching the entanglements with the anchoring cable or line.

Referring to the drawings, A designates a wire cable or other line to which are attached at suitable intervals floating propeller 95 entanglements B which terminate at their upper ends a few feet below the surface of the water, so that a floating battleship or other naval craft will be likely to encounter the floating entanglements and 100 have its propellers caught thereon, whereby the propellers will be rendered inoperative. The anchor line A is adapted to be laid by a light draft boat equipped like an ordinary cable layer, and the entanglements B are 105 adapted to be attached one after another as the anchor line A is paid out from the craft C. The end of the line A that is first thrown overboard will have a fluked anchor 1 so as to become firmly attached to 110

the sea bottom, and at intervals weighting anchors 2 are attached to the line A, these anchors being applied one after another as the line is being paid out. The lines may be of any desired length, according to the extent of the sea bottom to be covered. As shown in Fig. 2, the cables A may be laid parallel to each other, as indicated, and if desired there may be intersecting lines, whereby the entanglements will be planted very densely, rendering it impossible for the floating naval craft to traverse the area protected without the propellers becoming entangled and the craft made helpless.

The entanglement elements B are each made of flexible wire, rope or equivalent material and provided with buoyant means whereby the upper ends of the entanglements will be sufficiently close to the surface as to become readily entangled with propellers. In Fig. 1 a variety of forms of entanglements are shown. The upper ends may be of triangular formation, as shown at b, and each includes a float 3, and if desired a mine 4 may be embodied in the entanglement at any suitable point, the float being of sufficient buoyancy to keep the entanglement afloat. The entanglements b' have a rectangular formation at the top and include angularly disposed floats 5, and these entanglements may also include a floating mine 6. The entanglements may be of a multiform character, as shown at b², wherein the entanglement is shown as having the lower section somewhat like the form b, and attached to this lower section are a plurality of upper sections 7 and 8. This arrangement has an advantage that only one main connecting wire 9 is employed to connect a plurality of float-sustained entanglements with the anchoring cable A. It will be understood that when a floating or submarine craft encounters the field of propeller entanglement, the propellers will become caught on an entanglement and wind the latter up on the propeller and thereby disable the craft and render the same liable to destruction by the explosion of a mine that is incorporated in the entanglement. A mine net D may with advantage be used in connection with the system of propeller entanglements, and this net is adapted to be placed along the outer border of the entanglement system, and serves to prevent the passage of submarines through entanglements. This net D is made of wire or rope and has its bottom edge provided with anchors 10, and the upper edge is provided with floats 11, and distributed over the net are explosive mines 12 and dummy mines 13. If a submarine succeeds in passing through the field of entanglements by keeping at a level below the branched upper buoyant ends of the latter, and encounters the net D, there will be dan-

ger of destruction by explosion of the mines on the latter, and if the net is seen before it is reached there is likelihood of the propeller of the submarine boat becoming caught with the entanglements in maneuvering away from the net. The net D may have a microphone or equivalent device 14 which is connected by a wire 15 with a watch ship E, so that when a boat encounters the net the fact will be ascertained by the watch ship. The wire 15 may have branches 15' leading to the cables or entanglements, which latter will have microphones 14', as shown in Fig. 1, whereby the firing off of any of the mines, or the picking up of an entanglement by a propeller will be recorded or otherwise ascertained.

It is desirable that the anchors and the floating entanglements be capable of quick attachment to and detachment from the anchoring cable, so that the laying and taking up of the entanglements can be effected with despatch, and therefore the cable A may have snap hooks or equivalent devices 16, and the lower ends of the entanglements, as shown in Figs. 4 and 5, will be provided with eyes 17 to engage with the hooks. The anchors of the cable A may also be connected with similar snap hooks 16.

From the foregoing description taken in connection with the accompanying drawings, the advantages of the construction and method of operation will be readily understood by those skilled in the art to which the invention appertains, and while I have described the principle of operation, together with the system which I now consider to be the best embodiment thereof, I desire to have it understood that the system shown is merely illustrative and that such changes may be made when desired as are within the scope of the appended claims. Although the invention has been referred to as a defense, it is to be understood that this term is to include a blockade.

Having thus described my invention, I claim as new and desire to secure by Letters Patent:

1. A submarine defense comprising a plurality of looped propeller entanglements, an anchoring cable, and a connection extending from the bottom of each loop to the cable, each loop having float means for coöperating with the cable to maintain the loops more or less upright, and the float means also serving to hold the loops open for entanglement with propellers, said loops being independent of each other and free to move laterally in all directions from the anchoring cable.

2. A submarine defense comprising a plurality of looped propeller entanglements, an anchoring cable, a connection extending from the bottom of each loop to the cable, each loop having float means for coöperating

with the cable to maintain the loops more or less upright, and the float means also serving to hold the loops open for entanglement with propellers, and mines attached 5 to the loops, said loops being independent of each other and free to move laterally in all directions from the anchoring cable.

In testimony whereof I have signed my name to this specification in the presence of two subscribing witnesses.

ARTHUR N. McGRAY.
